DRESS-APRON ENSEMBLE

Carley Dawson, Washington, D. C.

Application May 3, 1950, Serial No. 9,681

Term of patent 3½ years

(Cl. D3—26)

To all whom it may concern:

Be it known that I, Carley Dawson, a citizen of the United States, residing at Washington, District of Columbia, have invented a new, original, and ornamental Design for Dress-Apron Ensemble, of which the following is a specification, reference being had to the accompanying drawing, forming part thereof.

In this showing:

Fig. 1 is a front view of the dress with apron and cuffs attached,

Fig. 2 is a rear view of the dress with apron and cuffs attached,

Fig. 3 is a front view of the dress without the apron and cuffs, while

Fig. 4 is a back view of the dress without the apron and cuffs.

I claim:

The ornamental design for a dress-apron ensemble, as shown.

CARLEY DAWSON.
